ELECTRIC COUPLING SYSTEM

Original application filed July 14, 1928, Serial No. 292,739, now Patent No. 1,763,380, dated June 10, 1930, and in Australia June 10, 1929. Divided and this application filed May 14, 1930. Serial No. 452,464.

This invention relates to electric coupling systems especially adapted for use with radio-frequency vacuum tube amplifiers, and more particularly to circuit arrangements which operate most effectively over a relatively wide range in frequency. The coupling systems are so arranged as to give a voltage ratio that varies automatically with the frequency. The variation in voltage ratio is accomplished in a primary circuit which includes a fixed self-inductance effectively in parallel with one or more fixed capacities external to the main resonant circuit and which may be electrically isolated from the main resonant circuit. The primary circuit is resonant at a frequency lower (but preferably not greatly lower) than the lowest frequency within the range of the coupling system. Coupling systems answering this description are described generally in the co-pending application for U. S. Letters Patent, Serial No. 292,739, filed July 14, 1928, patented June 10, 1930, No. 1,763,380, of which the present application is a division. The present application is confined to coupling systems in which the fixed self-inductance mentioned above is not electromagnetically coupled to the main resonant circuit, or if incidentally present, the electromagnetic coupling is so small as to make no apparent contribution to the performance of the system.

The voltage ratio in an inter-tube coupling system affects the degree of amplification, the stability and the selectivity. At each frequency there is a particular ratio of output voltage to input voltage that will give the best compromise design. This ratio varies rapidly with the frequency, being relatively high at high frequencies. This invention provides means for securing substantially the most desirable ratio at all frequencies without having any adjustable element except the tuning adjustment.

Referring to the drawings, Fig. 1 illustrates a vacuum tube and an electric coupling system embodying a simple form of this invention.

Fig. 2 illustrates a modification of Fig. 1 having an additional fixed capacity.

Fig. 3 illustrates a modification of Fig. 2 in which a two-coil transformer replaces an auto-transformer.

Fig. 4 illustrates a modification of Fig. 3 by which direct voltage is removed from the fixed capacity.

The coupling system of Fig. 1 is tuned by a variable condenser C_2 connected across the primary coil L_1 and the secondary coil L_2 in series. Ordinarily L_1 should have much fewer turns than L_2 so that there is a high step-up voltage ratio between them. The path through the primary coil L_1 from the plate of the vacuum tube to the filament includes also the fixed capacity C_5 which is external to the main resonant circuit C_2 , L_2 , L_1 . In parallel with this path is a second path including the self-inductance L_3 , the value of which is so chosen that its circuit (completed through C_5 and L_1) is resonant at a frequency lower, but not greatly lower than the lowest frequency within the range of condenser C_2 .

The circuit of L_3 , being completed through C_5 and L_1 , is thereby coupled to the main resonant circuit C_2 , L_2 , L_1 ; so that part of the current of C_2 and L_2 will flow through C_5 and L_3 , this part of the current being limited mostly by the reactance of L_3 . Since the reactance of L_3 varies directly with the frequency while that of C_5 varies inversely with the frequency, the voltage across C_5 will rapidly fall off relative to the voltage across L_1 as the frequency rises. For a given output voltage E_2 , the voltage across L_1 is very nearly independent of frequency, due to the electromagnetic coupling between L_1 and L_2 . Hence the voltage E_1 between the plate and the filament, being the sum of the voltages of C_5 and L_1 , will fall off relative to E_2 as the frequency rises, but less rapidly than the voltage across C_5 alone. This is the condition which is desired and which results in the maintenance of a high degree of stability over the frequency range, together with high sensitivity and selectivity.

The operation of the circuit of Fig. 2 is essentially the same as that of Fig. 1, but here the circuit of L_3 is completed through two parallel paths, that through C_3 and that

through C_5 and L_1 . As before, this circuit ⁵ L_3 , C_3 , C_5 , L_1 , should be made resonant at a frequency lower, but preferably not greatly lower, than the lowest frequency within the range of C_2 . The voltage ratio E_2/E_1 is obtained from a double step-up, first between C_3 and the combination of C_3 and C_5 , and then between L_1 and L_2 ; and, with the resonant condition just given, this voltage ratio ¹⁰ will automatically vary with the frequency in the same manner as in Fig. 1.

Fig. 3 differs from Fig. 2 only in that the primary coil L_1 is not included in the main resonant circuit. Coil L_1 should here have the same number of turns as in Fig. 2; while ¹⁵ the secondary coil L_2 should have the same number of turns as L_1 and L_2 , combined, in Fig. 2. The remaining relations are the same as in Fig. 2.

²⁰ In Fig. 3 the direct voltage of the plate battery B exists across condensers C_3 and C_5 , which is disadvantageous in that these condensers may break down. This difficulty is obviated in Fig. 4 by connecting the lower ²⁵ terminals of condenser C_3 and coil L_1 to the lower terminal of coil L_2 , instead of to the common lead at the bottom of the diagram. This connection does not affect the alternating-current relations of Fig. 4, which are ³⁰ identical with those of Fig. 3.

What is claimed is:

1. A radio-frequency coupling system having input terminals and comprising a main resonant circuit including as elements a coil ³⁵ and a condenser, at least one of which is adjustable to tune the coupling system over a range in frequency, a circuit coupled to said resonant circuit, including a fixed capacity and a fixed self-inductance effectively in parallel and having a resonant frequency lower, but not greatly lower, than the lowest frequency within said range, said fixed capacity being external to said resonant circuit and said self-inductance not being electromagnetically coupled to said resonant circuit, a circuit element having a fixed voltage ratio relative to said resonant circuit, and a path through said coupling system between said terminals including in series ⁴⁰ said fixed capacity and said circuit element, whereby there is developed in said resonant circuit a resonant voltage whose ratio to the voltage between said terminals automatically rises when said adjustable element is adjusted for higher frequencies.

⁴⁵ 2. In a radio amplifier stage including a vacuum tube having filament, grid and plate electrodes, an electric coupling system which comprises a main resonant circuit including as elements a coil and a condenser, at least one of which is adjustable to tune the coupling system over a range in frequency, a circuit coupled to said resonant circuit, including a fixed capacity and a fixed self-inductance effectively in parallel and having a ⁵⁰ resonant frequency lower, but not greatly lower, than the lowest frequency within said range, said fixed capacity being external to said main resonant circuit, whereby in the operation of the amplifier stage there is developed in said main resonant circuit a resonant voltage whose ratio to the voltage between the plate and

resonant frequency lower, but not greatly lower, than the lowest frequency within said range, said fixed capacity being external to said resonant circuit and said self-inductance not being electromagnetically coupled to ⁷⁰ said resonant circuit, a circuit element having a fixed voltage ratio relative to said resonant circuit, and a path through said coupling system between said plate and said filament including in series said fixed capacity and said circuit element, whereby in the operation of the amplifier stage there is developed in said resonant circuit a resonant voltage whose ratio to the voltage between the plate and the filament automatically rises when ⁸⁰ said adjustable element is adjusted for higher frequencies.

3. In a radio amplifier stage including a vacuum tube having a filament, a grid and a plate, an electric coupling system which comprises a main resonant circuit including as elements a secondary coil and a condenser, at least one of which is adjustable to tune the coupling system over a range in frequency, a circuit coupled to said resonant circuit, including a fixed capacity and a fixed self-inductance effectively in parallel and having a resonant frequency lower than the lowest frequency within said range, said fixed capacity being external to said resonant circuit and said self-inductance not being electromagnetically coupled to said resonant circuit, a primary coil electromagnetically coupled to said secondary coil, and a path through said coupling system between said plate and said filament including in series said fixed capacity and said primary coil, whereby in the operation of the amplifier stage there is developed in said resonant circuit a resonant voltage whose ratio to the voltage between the plate and the filament automatically rises when ⁹⁰ said adjustable element is adjusted for higher frequencies.

4. In a radio amplifier stage including a vacuum tube having a filament, a grid and a plate, an electric coupling system which comprises a main resonant circuit including as elements a coil and a condenser, at least one of which is adjustable to tune the coupling system over a range in frequency, a fixed self-inductance connected between said plate and said filament, said self-inductance not being electromagnetically coupled to said resonant circuit, a fixed capacity extending from said plate to said resonant circuit, said self-inductance and all of the capacity associated therewith being resonant at a frequency lower, but not greatly lower, than the lowest frequency within said range, all of said capacity being external to said main resonant circuit, whereby in the operation of the amplifier stage there is developed in said main resonant circuit a resonant voltage whose ratio to the voltage between the plate and

the filament automatically rises when said adjustable element is adjusted for higher frequencies.

5. In a radio amplifier stage including a vacuum tube having a filament, a grid and a plate, an electric coupling system which comprises a main resonant circuit including as elements a coil and a condenser, at least one of which is adjustable to tune the coupling system over a range in frequency, a first fixed capacity and a fixed self-inductance effectively in parallel between said plate and said filament, said self-inductance not being electromagnetically coupled to said resonant circuit, a second fixed capacity extending from said plate to said resonant circuit, said self-inductance and the capacity associated therewith being resonant at a frequency lower, but not greatly lower, than the lowest frequency within said range, all of said capacity being external to said main resonant circuit, whereby in the operation of the amplifier stage there is developed in said resonant circuit a resonant voltage whose ratio to the voltage between the plate and the filament automatically rises when said adjustable element is adjusted for higher frequencies.

6. A radio-frequency coupling system having input terminals and comprising a main resonant circuit including as elements a coil and a condenser, at least one of which is adjustable to tune the coupling system over a range in frequency, a second circuit coupled to said main resonant circuit, including a fixed self-inductance effectively in parallel with fixed capacity external to said main resonant circuit, said second circuit being resonant at a frequency lower, but not greatly lower, than the lowest frequency within said range, said self-inductance not being electromagnetically coupled to said main resonant circuit, a circuit element having a fixed voltage ratio relative to said main resonant circuit, and a path through said coupling system between said terminals including in series said circuit element and at least a portion of said fixed capacity, whereby there is developed in said main resonant circuit a resonant voltage whose ratio to the voltage between said terminals automatically rises when said adjustable element is adjusted for higher frequencies.

7. In a radio amplifier stage including a vacuum tube having a filament, a grid and a plate, an electric coupling system which comprises a main resonant circuit including as elements a coil and a condenser, at least one of which is adjustable to tune the coupling system over a range in frequency, a second circuit coupled to said resonant circuit, including a fixed self-inductance effectively in parallel with fixed capacity external to said main resonant circuit, said second circuit being resonant at a frequency lower, but not greatly lower, than the lowest frequency within said range, all of said capacity being external to said main resonant circuit, whereby in the operation of the amplifier stage there is developed in said main resonant circuit a resonant voltage whose ratio to the voltage between said terminals automatically rises when said adjustable element is adjusted for higher frequencies.

greatly lower, than the lowest frequency within said range, said self-inductance not being electromagnetically coupled to said main resonant circuit, a circuit element having a fixed voltage ratio relative to said main resonant circuit, and a path through said coupling system between said plate and said filament including in series said circuit element and at least a portion of said fixed capacity, whereby in the operation of the amplifier stage there is developed in said main resonant circuit a resonant voltage whose ratio to the voltage between the plate and the filament automatically rises when said adjustable element is adjusted for higher frequencies.

8. In a radio amplifier stage including a vacuum tube having a filament, a grid and a plate, an electric coupling system which comprises a main resonant circuit including as elements a secondary coil and a condenser, at least one of which is adjustable to tune the coupling system over a range in frequency, a second circuit coupled to said resonant circuit, including a fixed self-inductance effectively in parallel with fixed capacity external to said main resonant circuit, said second circuit being resonant at a frequency lower than the lowest frequency within said range, said self-inductance not being electromagnetically coupled to said main resonant circuit, a primary coil electromagnetically coupled to said secondary coil, and a path through said coupling system between said plate and said filament including in series said primary coil and at least a portion of said fixed capacity, whereby in the operation of the amplifier stage there is developed in said resonant circuit a resonant voltage whose ratio to the voltage between the plate and the filament automatically rises when said adjustable element is adjusted for higher frequencies.

9. A radio-frequency coupling system having input terminals one of which is at a higher average radio-frequency potential than the other, said system comprising a main resonant circuit including as elements a coil and a condenser, at least one of which is adjustable to tune the coupling system over a range in frequency, a fixed self-inductance connected between said terminals, said self-inductance not being electromagnetically coupled to said main resonant circuit, a fixed capacity extending from the higher-potential one of said terminals to said resonant circuit, said self-inductance and all of the capacity associated therewith being resonant at a frequency lower, but not greatly lower, than the lowest frequency within said range, all of said capacity being external to said main resonant circuit, whereby in the operation of the amplifier stage there is developed in said main resonant circuit a resonant voltage whose ratio to the voltage between said terminals automatically rises when said adjustable element is adjusted for higher frequencies.

minals automatically rises when said adjustable element is adjusted for higher frequencies.

10. In a radio amplifier stage including a vacuum tube having a filament, a grid and a plate, an electric coupling system which comprises a main resonant circuit including as elements a coil and a condenser, at least one of which is adjustable to tune the coupling system over a range in frequency, a first fixed capacity and a fixed self-inductance effectively in parallel between said plate and said filament, said self-inductance not being electromagnetically coupled to said resonant circuit, a second fixed capacity extending from said plate to said resonant circuit, said self-inductance and the capacity associated therewith being resonant at a frequency lower, but not greatly lower, than the lowest frequency within said range, all of said capacity being external to said main resonant circuit, whereby in the operation of the amplifier stage there is developed in said resonant circuit a resonant voltage whose ratio to the voltage between the plate and the filament automatically rises when said adjustable element is adjusted for higher frequencies, and whereby said fixed capacities effect a voltage step-up.
